KEY POUCH

Daniel J. Nash, New York, N. Y.

Application October 12, 1939, Serial No. 299,174

4 Claims. (Cl. 150—40)

This invention relates in general to key pouches or key cases for normally encasing keys and the like for convenient carriage in the pocket, hand-bag or the like, and permitting the keys to be projected or pulled from one end of the case for use. The case in general includes a flexible envelope or cover and a lazy tongs system of links within the cover or envelope for supporting and moving a key holder toward and from an opening in the envelope to project and retract keys on the holder through said opening out of and into the envelope.

One object of the invention is to provide a key pouch of the general character described which shall include a case, envelope or cover having a lazy tongs mechanism therein, and novel and improved means for permitting projection and retraction of the keys through an opening in the case into and out of the case.

Another object is to provide novel and improved automatic means for holding the keys in projected position for use and for releasing the projected keys at the will of the operator for retraction thereof into the case after use.

A further object is to provide such an automatic means for holding the keys in projected position which shall include a novel and improved latch or detent to cooperate with a part of the lazy tongs mechanism whereby a simple construction that is easy and positive in operation shall be obtained.

Other objects are to provide a key case of the character described which shall be simple, inexpensive, reliable and durable in construction and operation, and to obtain other advantages and results as will be brought out by the following description when read in conjunction with the accompanying drawing in which

Figure 1 is a plan view of a key pouch embodying my invention.

Figure 2 is a similar view with the upper portion of the case, envelope or cover removed, and showing the keys within the case.

Figure 3 is a view similar to Figure 2 showing the keys projected from the case.

Figures 4 and 5 are transverse vertical sectional views on the lines 4—4 and 5—5 of Figures 2 and 3, respectively.

Figure 6 is a vertical longitudinal sectional view on the line 6—6 of Figure 4, portions being broken away.

Figure 7 is a detached perspective view of the latch plate, and

Figure 8 is a view similar to Figure 2 showing a modification of the invention.

The pouch embodying the invention comprises a case, envelope or cover A of any suitable construction having an opening B, preferably at one end. As shown, the case is formed of flexible material such as leather and is composed of two similar pieces 1 secured together in superposed relation at their edges as by stitches 2.

Within the case is a key holding and ejecting mechanism C which is shown as comprising a lazy tongs system of links which includes a plurality of similar links 3. As shown, there are three pairs of the links 3, the links of each pair being connected at one end to the links of another pair as at 30, and the links of each pair being pivotally connected together substantially midway between their ends as at 4. The free ends of the pairs of links at one end of the system have pin and slot connections 5 with a key holder 6 that is shown in the form of a plate having a plurality of key holding loops or clips 7 pivotally or otherwise movably connected thereto and to which keys D are attached.

The free ends of the pair of links at the other end of the system are pivotally and slidably connected to the case to permit extension and contraction of the lazy tongs system. As shown, the links are connected at 8 to the respective approximately rectangular blocks 9 of suitable material which are slidably mounted to move toward and from each other in a guide channel 10 which is formed integrally with a supporting plate 11. As shown, the plate 11 has one end returned to form the channel, and the free edge has an inturned flange 12, whereby the guide pieces 9 are held against lateral movement in the guide channel. The pivot connecting the links of the pair which are connected to the guide pieces 9 is in the form of a pin 13 that is slidably mounted in a slot 14 in the supporting plate 11 and has a circumferential groove 130 engaging the plate at the edges of said slot, so as to guide the lazy tongs system and hold it against lateral movement away from the plate 11. With this construction the blocks 9 may slide toward each other in the guide channel 10 to permit the lazy tongs system of links to be extended as shown in Figure 3 by pulling upon one of the keys D to move the key holder 6 toward the opening B and project the keys on the clip 7 from the case through said opening.

For contracting the lazy tongs links so as to move the key holder 6 away from the opening B and retract the keys into the case, I have shown a spring which includes a helical coil 15 having its ends 16 pivotally connected to the joints be-

tween two adjacent pairs of links, as clearly shown in Figures 3 and 4. With this construction, the spring normally tends to draw the lazy tongs links together so as to contract the system of links as shown in Figure 2, and at the same time causes the blocks 9 to slide apart in the guide channel 10.

The supporting plate 11 is mounted at the end of the key case opposite the opening B and may be secured in the case in any suitable manner. As shown, the wall of the channel 10 is provided with a threaded opening 17 and the abutting wall of the case is formed with a registering opening 18, and a cap screw 19 passes through said openings, is secured into the opening 17 and has its head overlying the outer surfaces of said wall of the case. This provides a simple and inexpensive manner of securing the plate 11 and lazy tongs system in the case. If desired the plate may also be glued in the case.

With this construction, the key holder 6 and the associated keys D are normally encased as shown in Figure 2. When it is desired to use any of the keys, it is simply necessary to grip one of the keys between the thumb and index finger of one hand, and pull it outwardly. To facilitate gripping of the keys, the ends of the side walls of the case may be cut away as at 20. This will result in extension of the lazy tongs links to project the keys D from the case through the opening B as shown in Figure 3. Upon release of the keys, the spring 15 will tend to contract the lazy tongs links in the opposite direction so as to retract the keys into the case as shown in Figure 2.

In accordance with the invention, means is provided for temporarily holding the keys in projected position for use. As shown, a detent or latch plate 21 is pivotally mounted on the supporting plate 11 as by hooked arms 22 on opposite side edges of the plate disposed in the narrow portions of slots 23 in the supporting plate, the outer ends of which are enlarged at 230 to permit the arms 22 initially to be inserted therethrough and thereafter slid into the narrower portions for attaching the latch plate to the plate 11. One end of the latch plate is inclined at 24 toward the supporting plate 11, and this end is normally influenced toward the supporting plate by a spring 25 disposed between the supporting plate and the latch plate. One end of the pin 13 of the lazy tongs system projects above the surface of the supporting plate so as to be engaged by the inclined end 24 of the latch plate when the lazy tongs system is extended as shown in Figures 3 and 5.

The portion of the material of the case A overlying the detent plate 21 is sufficiently flexible to permit the plate to be oscillated by pressure of the fingers of the operator through the material and when the lazy tongs system is extended and it is desired to release said system to permit retraction of the keys in the case, it is merely necessary to press downwardly or inwardly upon the wall of the case above the end of the latch plate 21 opposite the inclined end 24, whereupon the end 24 will be raised out of engagement with the pin 13 and the pin will slide beneath the latch plate as the lazy tongs system contracts as shown in Figure 2.

If desired to prevent collapse of the wall of the case A at opposite sides of the latch plate, pads or the like 26 may be secured to the plate, and these pads may also be disposed to abut the latch plate and prevent it from sliding in such

a manner as to become released from the slots 23.

If desired, the blocks 9 may be made longer so as to project beyond the ends of the channel 10, and the side walls of the case may be formed with openings 27 through which the ends of the blocks may project outwardly from the case to serve as finger pieces, as shown in Figure 8. With this construction, when it is desired to project the keys from the case, it is simply necessary to grip the projecting ends of the blocks or finger pieces 9 between the thumb and index finger of one hand, and press the finger pieces or blocks toward each other. This will result in extension of the lazy tongs links to project the keys from the case through the opening B. The structure and operation of this form of the invention may be otherwise the same as that above described.

20 While I have shown and described the now preferred embodiment of the invention, it should be understood that the details of structure of the case may be widely modified and changed without departing from the spirit or scope of the appended claims.

Having thus described my invention, what I claim is:

1. A key pouch including an approximately flat case having an opening at one end, a key-holding and ejecting mechanism in said case including a lazy tongs system of links comprising a plurality of pivotally connected pairs of links each pair of which consists of two links pivotally connected intermediate their ends, a key holder pivotally connected to the links at the end of said lazy tongs system nearer said opening in the case, a rigid supporting plate mounted in said case adjacent the end thereof opposite said opening, means connecting the links at the other end of said system to one side of said supporting plate for movement relative to each other to permit extension and contraction of said lazy tongs system for movement of said key holder toward and from said opening, and a spring for contracting said lazy tongs system, said supporting plate having a slot, and the pivot connecting one pair of links being a pin slidable in said slot and having one end projecting from the side of said plate opposite said lazy tongs system, and a latch including a plate mounted on the last-mentioned side of said supporting plate to releasably engage said projecting end of said pin for holding said lazy tongs system extended.

2. A key pouch including an approximately flat case of pliable material having an opening at one end, a key-holding and ejecting mechanism in said case including a lazy tongs system of links comprising a plurality of pivotally connected pairs of links each pair of which consists of two links pivotally connected intermediate their ends, a key holder pivotally connected to the links at the end of said lazy tongs system nearer said opening in the case, a rigid supporting plate mounted in said case adjacent the end thereof opposite said opening, means connecting the links at the other end of said system to said supporting plate for movement relative to each other to permit extension and contraction of said lazy tongs system for movement of said key holder toward and from said opening, and a spring for contracting said lazy tongs system, the pivot of one of said pairs of links being a pin having one end projecting beyond the general plane of said lazy tongs system, a latch including a plate pivotally

mounted intermediate its ends on said supporting plate with one end to releasably engage said pin, and a spring to influence said end of said latch plate into engagement with said pin when said lazy tongs system is extended.

3. A key pouch including an approximately flat case of pliable material having an opening at one end, a key-holding and ejecting mechanism in said case including a lazy tongs system of links comprising a plurality of pivotally connected pairs of links each pair of which consists of two links pivotally connected intermediate their ends, a key holder pivotally connected to the links at the end of said lazy tongs system nearer said opening in the case, a rigid supporting plate mounted in said case adjacent the end thereof opposite said opening, means connecting the links at the other end of said system to said supporting plate for movement relative to each other to permit extension and contraction of said lazy tongs system for movement of said key holder toward and from said opening, and a spring for contracting said lazy tongs system, the pivot of one of said pairs of links being a pin having one end projecting beyond the general plane of said lazy tongs system, said supporting plate having a pair of openings, each with a narrow portion and an enlarged portion, a latch comprising a plate having hooked arms at opposite side edges and intermediate its ends which have been initially inserted through said enlarged portion of the respective opening of said supporting plate and then slid into said narrow portion whereby the latch plate is pivotally attached to the supporting plate with one end to releasably engage said pin, means on said supporting plate abutting opposite side edges of said latch plate to hold it in position with said hooked arms in said narrow portions of said openings, and a spring to influence said end of said latch plate into engagement with said pin when said lazy tongs system is extended.

4. A key pouch including an approximately flat case of pliable material having an opening at

one end, a key-holding and ejecting mechanism in said case including a lazy tongs system of links comprising a plurality of pivotally connected pairs of links each pair of which consists of two links pivotally connected intermediate their ends, a key holder pivotally connected to the links at the end of said lazy tongs system nearer said opening in the case, a rigid supporting plate mounted in said case adjacent the end 10 thereof opposite said opening, means connecting the links at the other end of said system to said supporting plate for movement relative to each other to permit extension and contraction of said lazy tongs system for movement of said key holder toward and from said opening, and a spring for contracting said lazy tongs system, the pivot of one of said pairs of links being a pin having one end projecting beyond the general plane of said lazy tongs system, said supporting plate having 15 a pair of openings, each with a narrow portion and an enlarged portion, a latch comprising a plate having hooked arms at opposite side edges and intermediate its ends which have been initially inserted through said enlarged portion of the respective opening of said supporting plate and then slid into said narrow portion whereby the latch plate is pivotally attached to the supporting plate with one end to releasably engage said pin, means on said supporting plate abutting opposite side edges of said latch plate to hold it in position with said hooked arms in said narrow portions of said openings, and a spring to influence said end of said latch plate into engagement with said pin when said lazy tongs 20 system is extended.

DANIEL J. NASH.
